Primary Examiner — Susan Moon Lee

(74) Attorney, Agent, or Firm — Vorys, Sater, Seymour and Pease LLP; Susanne M. Hopkins; William L. Klima

(57) **CLAIM**

The ornamental design for an animal feeder, as shown and described.

DESCRIPTION

FIG. 1 is a rear and right-side perspective view of an animal feeder,

FIG. 2 is a front and left-side perspective view thereof,

FIG. 3 is a rear elevational view thereof,

FIG. 4 is a front elevational view thereof,

FIG. 5 is a right-side elevational view thereof, the left-side being a mirror image,

FIG. 6 is a top planar view thereof; and,

FIG. 7 is a bottom planar view thereof.

No claim is made to color.

1 Claim, 7 Drawing Sheets(56)
